COMBINATION PUSH POLE AND PADDLE

Filed May 31, 1946

Inventor:
Ralph C. Johnson.

By: Sie & Sie Atty.

UNITED STATES PATENT OFFICE

2,477,410

COMBINATION PUSH POLE AND PADDLE

Ralph C. Johnson, Hill City, Minn.

Application May 31, 1946, Serial No. 673,536

7 Claims. (Cl. 9—24)

1

The invention relates generally to a manually operated device for propelling small boats or the like.

In the use of small boats, particularly those equipped with an outboard motor, or the like, it is desirable to carry a paddle or other device by means of which the boat may be manually propelled or guided in the event of motor failure, etc. Likewise, it is often times desirable to push the boat with a pole or other element, either away from piers and other objects or when grounded in shallow water where a paddle is of little use. Where a suitable push pole is not available a paddle is often times substituted for the pole, but as the former are not designed for such use, the paddle portion being relatively thin, they are easily broken.

The present invention has among its objects the production of a device which provides advantages of a paddle, at the same time retaining the strength to permit its use as a push pole.

Another object of the invention is the production of such a device which is relatively simple in construction and very efficient for the purposes intended.

A further object of the invention is the production of such a device which may be readily provided with a suitable hook for use in mooring the boat and the like.

Many other objects and advantages of the construction herein shown and described will be obvious to those skilled in the art from the disclosure herein given.

To this end my invention consists in the novel construction, arrangement and combination of parts herein shown and described and more particularly pointed out in the appended claims.

In the drawings where like reference characters indicate like or corresponding parts:

Fig. 1 is a front elevational view of the invention;

Fig. 2 is a front elevational view of the paddle end showing the details thereof;

Fig. 3 is a side elevational view of the paddle end of the device; and

Fig. 4 is an end view of the same end of the device illustrated in Figs. 2 and 3.

Referring to the drawings, the device illustrated comprises a shaft 1 of cylindrical cross section, one end 2 of which constitutes a handle, the opposite end 3 being provided with a suitable cap member 4 secured thereto by any suitable means, such as the rivet 5. Extending outwardly on opposite sides of the shaft 1, intermediate the handle 2 and end 3 of the shaft,

2

is a pair of paddle vanes 6, the latter in the present instance being formed integrally with the shaft 1. The outer edges 7 of the vanes 6 extend more or less parallel to the shaft 1, the end edges of the vanes adjacent the end 3 of the shaft being inclined outwardly and rearwardly as shown at 8 to prevent interference with the vanes 6 when the device is used as a push pole.

As illustrated in Figs. 3 and 4, the vanes 6 taper in thickness from adjacent the shaft 1 to the outer edges 7.

The cap 4 is provided with a hook 9 extending rearwardly from the cap towards the handle 2, the hook 9, as illustrated in Fig. 4, being positioned substantially in the plane of the vanes 6 so that the vane adjacent the hook 9 will be positioned directly over the tang of the hook and act as a guard therefor.

The device may be made out of any suitable material, as for example, wood or metal and where the shaft and vanes are made of a relatively soft material, such as wood, the cap 4 would preferably be made of metal to provide a reinforcing and protecting member for the end of the shaft. Obviously where the device would be made of metal, the cap 4 may if desired be formed as an integral part of the shaft.

It will be noted that the vanes 6 are spaced a sufficient distance from the end 3 of the shaft 1 to enable the device to be used efficiently as a push pole, the cap 4 preventing damage to the end of the shaft 1 when being so used.

It will also be noted that as the shaft 1 extends from one end of the pole to the other in more or less uniform cross section and as no force is applied to the vanes 6 when the device is being used as a push pole, adequate strength is achieved for such purposes. Similarly the extension of the shaft 1 below the bottom edges of the paddles will have relatively little effect on the operation of the device when used as a paddle.

The hook 9 is of particular use in picking up mooring lines and the like, as for example, when mooring the boat to a buoy and as the tang of the hook is positioned directly below the edge 8 of the adjacent vane, there is little tendency of the hook to become snagged upon other objects, particularly when used as a push pole as the vanes 6 will tend to ward off objects that might otherwise engage the tang of the hook.

It will be apparent from the above description that I have provided a single device which may be employed for launching or mooring a boat and which, if necessary, may also be utilized to propel the same, as a result of which it is un-

necessary to provide other equipment to perform these functions with a consequent saving of weight, space and expense.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. In a device of the kind described, the combination of an elongated shaft, one end of which constitutes a handle, a reinforcing cap secured to the opposite end having a hook portion thereon extending rearwardly towards the handle, and a pair of paddle vanes carried by said shaft and extending outwardly from opposite sides of said shaft, intermediate the handle and capped end thereof, said vanes being positioned substantially in a common plane, said hook portion lying substantially in the plane of said vanes, the end edges of the latter adjacent the capped end of said shaft being inclined outwardly and rearwardly towards the handle end thereof.

2. In a device of the kind described, the combination of an elongated shaft, one end of which constitutes a handle, a reinforcing cap secured to the opposite end having a hook portion thereon extending rearwardly towards the handle, and a pair of paddle vanes carried by said shaft and extending outwardly from opposite sides of said shaft, intermediate the handle and capped end thereof, said vanes being positioned substantially in a common plane, said hook portion lying substantially in the plane of said vanes.

3. In a device of the kind described, the combination of an elongated shaft, one end of which constitutes a handle, a pair of paddle vanes carried by said shaft and extending outwardly from opposite sides thereof, said vanes being positioned substantially in a common plane, adjacent to but spaced from the opposite end of said shaft, and a reinforcing cap covering the latter end of said shaft, and having a blunt object engageable end face.

4. In a device of the kind described, the combination of an elongated shaft, one end of which constitutes a handle, and a pair of paddle vanes carried by said shaft and extending outwardly from opposite sides thereof, said vanes being positioned substantially in a common plane, adjacent to but spaced from the opposite end of said shaft, the end edges of the vanes adjacent said opposite end of the shaft being inclined outwardly and rearwardly towards the handle end thereof.

5. In a device of the kind described, the combination of an elongated shaft of approximately uniform cross section throughout its length, one end of which constitutes a handle, a reinforcing cap secured to the opposite end having a hook portion thereon extending rearwardly towards the handle end, and a pair of paddle vanes carried by said shaft and extending outwardly from opposite sides thereof, said vanes being positioned substantially in a common plane, adjacent to but spaced from the capped end of said shaft, said vanes tapering in thickness from the shaft towards their outer edges, said hook portion lying substantially in the plane of said vanes, the end edges of the latter adjacent the capped end of said shaft being inclined outwardly and rearwardly towards the handle end thereof.

6. In a device of the kind described, the combination of an elongated shaft, one end of which constitutes a handle, a reinforcing cap secured to the opposite end of said shaft, and a pair of paddle vanes carried by said shaft and extending outwardly from opposite sides thereof, the end edges of the vanes adjacent said opposite end of the shaft being inclined outwardly and rearwardly towards the handle end thereof.

7. In a device of the kind described, the combination of an elongated shaft of approximately uniform cross section throughout its length, one end of which constitutes a handle, a reinforcing cap secured to the opposite end having a hook portion thereon extending rearwardly towards the handle end, and a pair of paddle vanes carried by said shaft and extending outwardly from opposite sides thereof, said vanes being positioned substantially in a common plane, adjacent to but spaced from the capped end of said shaft, the end edges of the vanes adjacent the capped end of said shaft being inclined outwardly and rearwardly towards the handle end thereof.
